UNITED STATES PATENT OFFICE

1,937,530

MATCH PACKAGING MACHINE

Rodney S. Pullen, William F. Casey, and George M. Thomas, Philadelphia, Pa., assignors, by direct and mesne assignments, to Pullenlite Company, Philadelphia, Pa., a corporation of Pennsylvania

Application July 12, 1928. Serial No. 292,210

55 Claims. (Cl. 93—2)

Our invention relates to a machine for automatically packaging matches with particular reference to a machine for putting up matches into book packages of the same general form of package or book that has been disclosed and claimed by Rodney S. Pullen in a United States patent application #186,097, filed April 23, 1927, and entitled "Match book."

The purpose of our invention is to provide a machine adapted to easily and rapidly assemble match books from matches, paper blanks and metal strip material, the matches preferably being delivered automatically from a hopper, the paper blanks comprising scored cards carrying suitable ignition coatings at positions to be simultaneously engaged by the match heads when the matches are withdrawn by the user from the package, and the metal baling strip preferably being fed automatically from a suitable roll of metal strips.

A further purpose is to effect all the movements of the operating parts of a match packaging machine from a single cam shaft, letting each rotation of the shaft advance the package one step and effect one complete cycle for each of the operating members other than the conveyer which is operatively connected to the cam shaft and advanced one step by each rotation of the shaft.

A further purpose is to convey successive charges of matches for successive match books in upwardly presented transverse grooves across blocks carried by an endless conveyer, each block having as many groove seats as there are matches to be threaded into each book and being adapted to present the matches in position for threading into a book.

A further purpose is to provide the blocks of an endless conveyer that receive automatic charges of matches in groove seats when the blocks are at one position of dwell and present them for automatic threading into match packages at another position of dwell with intermediate positions of dwell in order to permit hand insertion of matches at any groove or grooves not properly charged by automatic mechanism.

A further purpose is to operate the delivery of matches from a match supply hopper on to a match conveying unit by the movement of mechanism that effects the discharge of the matches from the unit at a later position thereof.

A further purpose is to push the matches into the groove seats of successive match carrier units of a match conveyer with the head-ends of the matches foremost by pushing the stick ends and subsequently discharge the matches stick-end

foremost by pushing the head-ends. We thus avoid jamming the matches during delivery from the match supply hopper by reason of wedge action due to the matches having a greater thickness at their heads than at their sticks, and discharge the matches, stick-ends foremost so that the stick-ends may thread suitable perforations in a formed card.

A further purpose is to provide a mechanism for exactly registering each match carrier block of a match conveyer in its discharging position of dwell, preferably using a pin and socket registry in which a pin having its upper side chamfered away moves up successively into the downwardly presented sockets of the carriers when they come to dwell in discharging position, the sockets successively fitting the pin, which moves out of its registry position when each carrier unit discharges its matches and before its period of dwell is completed.

A further purpose is to move the match carrier blocks of a match conveyer along horizontal guides to maintain their exact alignment when between the match charging and match discharging positions of dwell.

A further purpose is to move the loaded match carrying blocks successively under a stationary cover before they reach discharging position, a cover that extends over the groove seats of blocks in the discharging position so that during discharge the matches are encased in covered grooves and may not deflect upwardly when pushed out of their groove seats by the threading rods.

A further purpose is to make the groove match seats on the match carrying blocks of a match conveyer slightly greater than the average match length, so as to permit operation with different lengths of matches.

A further purpose is to enclose a pile of blanks in a blank supply hopper, to deliver the blanks successively from the bottom of the pile by means of a plunger plate presented along the greater portion of the length of the bottom blank and having a thickness not greater than and preferably slightly less than the thickness of the average blank.

A further purpose is to maintain exact forward registry of the forward ends of the cards with respect to the downwardly presented face of a card-forming and match-guiding plunger, by means of a spring-pressed plate pressing against the rear end of the card to maintain its forward end against a suitable rearwardly presented gage surface while the card is being transferred to

- position beneath the plunger. The necessity for this registry is due to the fact that registry between scoring lines on the blank and an operating head that forms the blank into shape to receive 5 the matches through scored holes. 80
- A further purpose is to provide a form of paper-blank supply hopper that gives easy access to any bottom blank that has inadvertently failed to properly deliver by forming the hopper to permit easy 10 removal of all blanks from the hopper. 85
- A further purpose is to obtain an adequate and substantially uniform downward pressure upon the upper surface of the bottom card of a pile of blanks inside a hopper by a weight upon the 15 top of the pile, preferably providing this weight with spaced transversely extending feet that engage the top card at particular points of the pile that best adapt the weight to provide the bottom card with uniform pressure over its whole length. 90
- 20 The locations of the feet are best determined by experiment. 95
- A further purpose is to push the cards that are delivering from the hopper into a guideway that is stationary along the front of the delivery card 25 and along the rear of the delivering card presents a groove surface resiliently pressing forward so as to face the front edge of the card against the forward guide for proper registry with a forming guide. 100
- 30 A further purpose is to depress a flat card carrying two longitudinally spaced transverse rows of perforations for threading a row of matches, each match through one perforation of each row, so that the portion of the card intermediate the 35 rows of perforations is depressed and the perforations are turned up transversely in line with one another and in line with match guiding mechanism that is adapted to guide match sticks to 105 thread the aligned perforations.
- 40 A further purpose is to provide groove match stick guides that are adapted to definitely register an alignment of match sticks by reason of seating the stick sections too closely to pass the match heads and that are adapted to move out of 45 the way of the match heads when the matches are being pushed inwardly after the match sticks have threaded aligned holes in a card and before the match heads have their desired inward position, the entrances to the grooved guides being preferably flared for more easy entry of the 50 match sticks. 110
- A further purpose is to combine a match guiding member with a blank forming member, making the descent of the member form the blank for 55 receipt of the matches and at the same time present groove guides in alignment with the matches to position the matches in the package and to enable the sticks to properly thread rearward holes of the blank after having been pushed 60 through the holes at the front. 115
- A further purpose is to automatically lift a partially formed match package to clear forming and guiding recesses used to thread matches into the package, by means of a stripper plate spring 65 pressed upwardly from one of the recesses and depressed by a plunger that, in low position forms the blank and presents guides to the threading matches. 120
- A further purpose is to obtain definite registry 70 between the adjacent edges of a card leaving a card hopper and of a card that has just had a row of matches threaded into it by means of a downwardly pressing presser foot engaging the upwardly presented sides of the match sticks. The 75 presser foot is presented above the stripper plate 125
- transversely across the middle of the matches, is chamfered off at the front side of the matches so that the matches can enter under the plate and press the plate upward to any requisite extent, the plate holding the row uniformly downward, is supported from the housing of the forming and guiding plunger, and extends beneath the plunger under a suitable transverse recess across the bottom of the plunger. 130
- A further purpose is to push a card that has just been threaded with matches away from the position for match threading by the next card entering the position for match threading. 135
- A further purpose is to extend the resiliently downwardly pressing presser foot to overlap the second position of the package from the head so as to insure registry between the blank that has just been discharged with that which is in the position ahead of the charging position. 140
- A further purpose is to push a row of matches side by side along groove guideways by means of push rods side by side, delivering successive charges of matches from successive match carrying blocks of a match conveyer to thread successive blanks. 145
- A further purpose is to have the push rods present cupped ends to the match heads so as to insure a horizontal pushing engagement, and to have the rods longitudinally adjustable to accommodate different lengths of matches. 150
- A further purpose is to mount match push rods and mechanism for turning in the side edges of the up-turned flap of a blank that is being charged with the matches upon the same plunger so that the forward stroke of the plunger may 155 simultaneously thread the matches into the blank and turn in the side edges of the up-turned flap. 160
- We rigidly fasten the turn-in members of the mechanism to the match charging plunger in position to engage the edge portions of the flap, 115 edge portions which overlap the vertical outside edges of structure back of the flap, and mount on the turn-in mechanism a stripper plate intermediate the turn-ins and normally pressing out to the ends of the turn-ins, the stripper plate 120 throughout the turn-in stopping against the portion of the upturned flap that is intermediate the turn-ins. 125
- A further purpose is to push a card that has received its charge of matches to its next position by means of the next card advancing to the match charging position. 130
- A further purpose is to use the movement of the plunger that delivers the successive blanks out of the blank supply hopper to move mechanism for mechanically advancing the charged blanks after they have been pushed out of match charging position. 135
- A further purpose is to provide either a ratchet or a point engagement between a match packet 140 transfer mechanism and a match packet that has been charged with matches, and already moved away from the match charging position. 145
- A further purpose is to use the movement of a match charging plunger to operate a flap turn-down member operative at a position subsequent to that for match charging and before that for baling. 150
- A further purpose is to leave sufficient clearance between the uncompleted match packet in 145 flap turn-down position and that in baling position in order to provide room for operation of members that partially clinch the bale over the bottom of the packet to adapt the bale to stay in place during its transfer to looping and clinch- 155

ing positions and during the looping operation.

A further purpose is to outwardly spring press the inside crease of a turn-down flap during the turn-down operation. A spring under the turn-down flap straightens out when the turn-down plunger moves over the flap to effect turn down, the chamfered advancing edge of the turn-down sweeping the flap down upon the bowed spring, depressing the bow of the spring to lengthen the spring so that its front edge presses into the turn-down crease of the flap immediately beneath the plunger giving a sharp turn at the crease.

10 A further purpose is to maintain a turn-down flap in turn-down position after the retraction of the turn-down plunger and until the packet has been delivered to its next position by using the forward movement of the turn-down plunger to press the edge of the flap under a downwardly directed stationary ledge or guide member in front of the up-turned rearward flap.

15 A further purpose is to let the downwardly directed face that holds the front flap down after the turn-down operation have an upward slope forwardly so that when the package is moved toward its next position, that for baling, frictional resistance to the movement of the packet becomes progressively less by reason of the gradual relief of the tension between the upper side of 20 the flap and the downward side of the gude. This ledge or guide maintains the front flap down until it is far enough advanced to be held down by a spring upon the carrier and raised somewhat from the carrier surface, the raised 25 spring then maintaining the flap so that it is still down when the packet reaches its baling position although it has by this time been moved beyond the guiding ledge along its edge.

30 A further purpose is to advance the uncompleted match packet into position for baling by the medium of the next advancing packet, either stopping the advancing movement of the rearward packet before the forward packet is all the way to its position for baling, or else moving the rearward packet forwardly, and then backwardly 35 a short distance in order to be out of the way of mechanism for partially clinching the bale in order to hold the bale to place for subsequent transfer and looping operations preparatory to 40 final clinching.

A further purpose is to progress the packet to exact position for baling by wedge action of members carried upon a bale forming die.

45 A further purpose is to give the wedges that move the package to position for baling rounded engagement surfaces in order to secure more efficient action.

50 A further purpose is to support the packets from below closely adjacent the downwardly moving wedges that register the packet into position for baling.

55 A further purpose is to provide a transfer slide in which the slide offers the packet advancing to baling position a horizontal support across its lower surfaces, a horizontal support that is adapted to yield downwardly to accommodate the downwardly curved surface presented by the die and bale.

60 A further purpose is to provide a transfer slide for supporting a packet in dwell during the baling operation and for subsequently transferring it to looping position with a movable jaw that will remain open or raised during the baling operation and while open or raised will hold the 65 front flap of the packet from rising and that will

resiliently close down upon the packet when the packet moves from baling position.

A further purpose is to periodically deliver a definite length of bale between forming dies, in synchronism with the progression of the package and while the package is in position to receive the bale.

70 A further purpose is to provide a punch die mechanism by which the punch on its downward movement shears a definite length of baling material, forms it against a lower form die that has temporarily moved out to dwell in front of the downwardly moving punch, having the lower die move back out of the way of continued downward movement of the upper die, having the upper die provided with mechanism, preferably magnetic, for holding the formed bale to position upon the upper form after the lower die moves away, and having the upper die move further downward, and in its downward movement 75 preferably registering the package upon a transfer slide below, then using the upper die to hold the bale to place upon the turned down fold of the match packet for the operation of partial clinching members that move up and bend the ends of the bale inwardly under the packet and then after releasing the magnetic hold moving up out of the way to permit transfer of the packet upon the transfer slide for looping and 80 clinching.

85 A further purpose is to operate a vertically moving bale forming punch member in a vertical guide by means of a lost movement connection with an operating rocker arm, and to prevent any sudden drop of the punch by a suitable 90 spring brake.

95 A further purpose is to have die members that form the outer right bends on the bale swing laterally outward after their forming operation and continued downward movement, to be out 100 of the way during the downward movement of the punch out of the way of members that turn the bale ends under the packet to hold the bale in place after the punch member retracts upward. The die members are preferably spring 105 pressed toward operating position and forced outward when the punch moves downward.

110 A further purpose is to use wedges mounted upon a punch member that presents a bale against a match packet to register the packet 115 with respect to the punch member and the downwardly presented bale.

115 A further purpose is to provide a forwardly presented ledge surface on the bottom of the punch member in position to engage the rearward side of the bale in order to prevent the bale from moving rearwardly when the lower die member moves back out of the way, the bale seating against this stationary ledge presented by the punch.

120 A further purpose is to provide a die member that is presented beneath a bale below a bale forming punch with a forwardly extending resilient projection that relieves the bale from any material spring downward at the time of its disengagement with lower forming die when the lower forming die member moves back.

125 The purpose of this forward projection is to prevent sudden downward spring of the bale away from the magnetic holding member. Such 130 sudden springing may break the hold between the magnet and bale unless the magnet is stronger than would otherwise be necessary.

130 A further purpose is to tighten the gripping 135 between the holding mechanism and the flap by 140

- the forward operation of the transfer slide to its next position, a cam releasing the spring so that it snaps down against the flap pressing the flap on to the matches. 80
- 5 A further purpose is to spring-press the transfer slide toward an intermediate position in order to avoid overtravel of the slide in either direction due to spring in the levers that operate the carriage. This spring pressure toward an 10 intermediate position makes the carriage come gradually to rest at both ends of its travel due to the gradual increase in the resistance that the carriage meets as it moves toward either end of its travel. Preferably the spring tension tending 15 to retract the carriage toward an intermediate position, is greater when the carriage is at the forward end of its travel than when it is in its rearward position for the operating of the looping and clinching mechanism. 15
- 20 A further purpose is to provide vertically centering guides back of the up-turned portion of the flap so that when the transfer slide moves rearwardly it automatically centers the package upon the slide. These vertical plates do not push 25 the flap down but merely properly guide it centrally. If one of these vertically guiding walls engages the adjacent side of the upwardly turned rearward flap it straightens up the package so that the match heads press against a forwardly-directed face of the carrier that is immediately 30 in front of the match heads. 30
- 25 A further purpose is to use the rearward movement of the transfer slide to force the rearwardly directed match sticks of the packet between upper and lower horizontal gripper jaws, forwardly 35 chamfered to permit the sticks to wedge them apart, so that when the slide reaches its rearward position the sticks of the packet are firmly gripped from following the slide when it returns 40 to its forward position. 40
- 30 A further purpose is to mount a rearward flap turning or looping member operative when the transfer slide retracts forwardly to fold the rearward flap down forwardly over the threaded 45 matches and then up rearwardly to engage the bottom of the packet. 45
- 35 A further purpose is to provide the lower horizontal gripper member with a forwardly projecting finger that extends forwardly so that when a packet is in looping position the finger lies along and below the middle of the packet across the 50 row of perforations for threading the matches, and downwardly swells the upwardly turned flap so as to shorten the distance between opposite 55 edges of the flap when it is looped around for insertion beneath the half-turned ends of the bale. 55
- 40 A further purpose is to provide a looping mechanism that is pivoted in an axis substantially coincident with the upper forward corner 60 of the packet when the packet is in looping position, the looping mechanism being provided with an angle that is adapted to square the package when the looper is in its final position and being 65 provided with arms and cross bar connection between the arms that swing the flap down and around the match heads and then rearwardly upwardly to press the flap so that under edges of the flap enter between the partially crimped 70 bale ends. 70
- 45 A further purpose is to finally clinch the partially clinched bale ends while the package is held between the stick grippers. 75
- 50 A further purpose is to simultaneously clinch the bale ends by means of double wedge actions, 75
- 55 using one set of wedges to place two sets of double jaws so that one set of jaws encloses one bale end and the other set of jaws encloses the other bale end and to use the other wedge action to rock an operating gripper member that closes the jaws simultaneously to clinch the bale ends simultaneously. 80
- 60 A further purpose is to provide a kick discharge of the packages after the completion and release of the clinching operation. 85
- 65 Further purposes will appear in the specification and in the claims. 90
- 70 We have elected to illustrate our invention in one only of its forms in general with respect to many details that are adapted to be widely varied, but have selected a form of machine and forms of details that have proven to be practical and efficient in operation and that well illustrate the principles involved. 95
- 75 Figure 1 is a perspective assembly view of a machine embodying our invention, looking toward the front of the machine. 100
- 80 Figure 2 is a perspective assembly view of the structure shown in Figure 1, looking toward the rear of the machine. 105
- 85 Figure 3A is a top plan view of a scored and perforated paper blank, coated with ignition material and ready to be supplied to the machine for assembly with matches and a piece of bale strip into a match book. 105
- 90 Figure 3B is an enlarged fragment of Figure 3A, illustrating the petticoated holes with staggered petticoat scorings. 105

Figure 11 is a front elevation of the blank supply hopper and shows the end of the blank feeding plunger at the left and the bracket supporting the hopper and providing a housing for the blank-forming and match-guiding plunger at the right.

Figure 12 is a side elevation of structure shown in Figure 11.

Figure 13A is a plan view of the blank supply hopper and shows structure for rear adjustments of the blanks to give the blanks uniform front registry when they reach match receiving position.

Figure 13B is a section taken upon the line 13B—13B of Figure 13A. The view is to enlarged scale and illustrates the arrangement for making the front of the blanks register always in the same vertical plane when they reach match receiving position.

Figure 14 is a fragmentary front elevation of structure toward the right hand end of the machine.

Figure 15 is a fragmentary plan view of Figure 14.

Figure 16A is a section taken upon the line 16A—16A of Figure 15.

Figure 16B is a section taken upon the line 16B—16B of Figure 15, illustrating the plunger that feeds the paper blank from the supply hopper into position to receive the matches.

Figure 16C is a detail section taken upon the line 16C—16C of Figure 16A.

Figure 16D shows the structure of Figure 16C in a different position, with the stripper plate depressed and uncovering stationary match stick guiding grooves that are back of the plate when the stripper is in its normal raised position.

Figure 17 is a vertical section corresponding to the line 17—17 of Figure 18 and is generally similar to Figure 16A but shows more structure than shown in the latter figure. It is a cross section through parts that effect the match loading into the paper blank.

Figure 18 is a top plan view of Figure 17.

Figure 19A is a fragmentary vertical section upon the line 19A—19A of Figure 18 showing the card beneath the card-forming and match-guiding die and the matches threading through the blank, not yet all the way in, the match stem guide still in raised position and the short flap edge turn-in not yet engaging the edges of the turned-up short flap.

Figure 19B is a fragment of 19A except that the parts are advanced, the matches having been pushed all the way in, the match stem guide having moved down to permit passage of the match heads and the short flap edge turn-ins all the way in, turning in the edges of the turned-up flap.

Figure 19C shows the same parts a little later, with the push rods, short flap edge turn-ins and the card-forming die all retracting and the card threaded with matches lifted in position to be advanced by the next card.

Figure 19D is a horizontal section corresponding to the line 19D—19D upon the Figure 19A but with the parts in somewhat different position.

Figures 19E, 19F and 19G are fragmentary sections taken upon the lines 19E—19E, 19F—19F and 19G—19G respectively of Figure 19D.

Figure 20A is a front elevation of mechanism for forwardly feeding the packet after it has been delivered from the match loading position.

Figure 20B is an end view of Figure 20A, cor-

responding to a section upon the line 20B—20B of Figure 20A.

Figure 21A is a vertical section through a packet and adjacent structure in position of short flap turn-down, showing the flap turn-down plunger about to move forward, and corresponds to section upon the line 21A—21A of Figure 21C.

Figure 21B is a view generally similar to Figure 21A but with the turn-down plunger advanced to effect turn down and having in advancing turned the flap down so that its edge has passed under a stationary flap guide in front of the up-turned long flap.

Figure 21C is a detail plan view of Figure 21A and showing packets intermediate the hopper and baling positions.

Figure 22A is a detail plan view of the bale feeding mechanism.

Figure 22B is a front elevation of structure shown in Figure 22A.

Figure 23 is a side elevation of the bale feed mechanism showing the bale between rolls, the upper roll spring pressing the bale down against the lower roll.

Figure 24 is a front elevation of structure shown in Figure 23 and includes at the left mechanism not shown in the latter figure for bale cutting and forming.

Figure 25 is a rear elevation of structure toward the right end of the machine and shows the relation between the loading, baling, clinching and match conveyor mechanisms.

Figure 26 is a front elevation of structure toward the left end of the machine.

Figure 27 is a false section taken upon the line 27—27 of Figure 14 and shows inter alia the bale forming unit and the transfer slide mechanism.

Figure 28A is an enlarged detail vertical section taken upon the line 28A—28A of Figure 27 and showing the different parts in bale forming position.

Figure 28B shows the same structure shown in Figure 28A with the parts advanced, depositing a formed bale upon a match packet.

Figure 29A is a vertical section taken upon the line 29A—29A of Figure 28B.

Figure 29B is a fragmentary plan view of a detail shown in Figure 29A and may be considered as a horizontal section taken upon the line 29B—29B of the latter figure.

Figure 30 is a false vertical section taken upon the line 30—30 of Figure 31 and the line 30—30 of Figure 32 and shows looping mechanism and the mechanism for partial clinching the bale to hold the bale temporarily in place.

Figure 31 is a front elevation of the structure shown in Figure 30.

Figure 32 is a plan view showing mechanism of the transfer slide, looper, bale and bale clinching.

Figure 33A is an enlarged scale fragment of Figure 27 and illustrates match stick gripping mechanism for holding the packet after the transfer slide has moved forwardly out of the way, and shows part of the looping mechanism.

Figure 33B is a front elevation of parts shown in Figure 33A, corresponding to a section upon the line 33B—33B of Figure 33A.

Figure 33C is a front view of a detail and corresponds to a section taken upon the line 33C—33C of Figure 33A and shows a vertical adjustable stop plate for registering the package for the clinching operation.

Figure 33D is an enlarged fragmentary section taken upon the line 33D—33D of Figure 33C.

Figure 34 is a detailed plan view in part section of structure for effecting looping and final clinching, with particular reference to the clinching mechanism.

Figure 35A is a vertical section, half-full elevation, taken upon the line 35A—35A of Figure 34, showing clinching mechanism with the clincher jaws nearly in position for final clinching.

Figure 35B is a fragment of Figure 35A showing the parts in different position, that in which the bale has just been finally clinched on to the folded packet.

Figure 35C is a vertical section corresponding generally to that upon the line 35C—35C of Figure 34 and shows the operating lever of the clinchers in position of final clinching.

Figure 36A is a fragmentary diagrammatic plan view of structure at the card supply hopper showing the card blank about to be moved by the card feeding plunger into position for forming for match receiving.

Figure 36B is a section taken upon the line 36B—36B of Figure 36A.

Figure 36C is a view corresponding generally to Figure 36A but with the parts in advanced position, the blank having moved to position to receive the matches.

Figure 36D is a section taken upon the line 36D—36D of Figure 36C.

Figure 36E is a plan view of Figure 36F taken beneath the forming and guiding plunger and shows the matches ready to enter the forward row of holes in the blank.

Figure 36F is a section taken upon the line 36F—36F of Figure 36E and shows the flap edge turn-in mechanism ready to operate to turn in the flap edges of the forward flap.

Figure 36G is a plan view corresponding generally to Figure 36E but with the parts advanced, the matches having been moved to place in the packet.

Figure 36H is a section taken upon the line 36H—36H of Figure 36G. It corresponds to Figure 36F with parts advanced, the short flap edge turn-ins in forward position.

Figure 36J is a plan view showing the matches in the packet after the forming plunger has lifted and the match charging plunger has withdrawn, the packet being ready to be advanced to the first idle position.

Figure 36K is a vertical section on the line 36K—36K of Figure 36J.

Figures 37A to 38D inclusive are vertical sections, partially diagrammatic, corresponding generally to Figure 36K but showing successive positions of parts and packets as a first packet progresses from the match charging position toward baling position.

Figures 39A to 39C inclusive are views taken in the same vertical plane as Figures 37A to 38D inclusive, showing structure to the right of that shown in the latter figures and show positions of a packet and adjacent operating parts of the machine during baling.

Figure 39D is a horizontal section upon the line 39D—39D of Figure 39C and shows the transfer slide about to insert the rearwardly projecting match sticks between the jaws of gripper mechanism to the right and also shows looping mechanism in raised position.

Figure 39E is a vertical section upon the line 39E—39E of Figure 39D.

Figure 39F corresponds generally to Figure 39E but with the transfer slide advanced so that the match sticks are gripped in the gripping mechanism at the right, the transfer slide being ready to retract forwardly to the left.

Figure 40A is a fragmentary vertical section illustrating the transfer slide in receiving position, the looper still raised, and the packet supported by the rearwardly extending match sticks gripped by the gripper jaws at the right.

Figure 40B shows the same structure, the slide in its retracted forward receiving position and the looper having swept the long blank around into its position for final clinching.

Figure 40C is a vertical section similar to Figure 35A and showing the finger from the lower jaw of the gripper bulging the packet so that it may enter between the bale ends and the clincher jaws ready to move into clinching position.

Figure 40D is a section generally similar to Figure 39E showing the support slide under the finished packet having been withdrawn and the finished packet thrust out by the upper jaw mechanism.

Like reference characters refer to like parts in all figures.

Describing in illustration and not in limitation and referring to the drawings:—

The illustrated embodiment of our invention is best shown in Figures 1 and 2 which are respectively front and rear perspective assembly views of a complete machine that has proved to be effective and efficient in operation.

The function of the machine is to assemble matches A, scored and perforated cards B and strip bale material C into match books that are in general accord with that disclosed in the co-pending application of Rodney S. Pullen already referred to.

The match book and the cards and bale strip material used in the assembled book are shown in Figures 3A, 3B, 3C, 3D and 3E and are described in order to make clearer the application of different features of our machine.

Figure 3A shows the inside face of one of the cards that are piled in a card feed hopper B1 of the machine.

The inside face of the card when placed in the hopper B1 is scored along the lines 1, 2, 3, 4, 5, 6, 7, 8, 9, 10 and 11, cut through at 12 and 13, coated with ignition material over the areas 14 and 15 and is provided with a transverse row of petticoated holes 16 between the score lines 7 and 8 and a second transverse row of holes 17 between the score lines 4 and 5, the latter holes 13 being preferably cleanly cut.

The petticoats of adjacent petticoated holes 16 are relatively staggered as illustrated in the enlarged fragment (Figure 3B) in order to increase the distance between the radial cuts 18 of one hole from the corresponding cuts 19 of the adjacent holes which avoids unduly weakening the card along the row of petticoated holes.

The card is folded up along the lines 5 and 7 so that the holes of both rows are vertical and matches, stick-end forward, are threaded first through the petticoated holes 16 and then through the clean cut holes 17, the match heads seating in the inwardly deflected petticoats as seen at 20.

The edges of the short flap are then turned in along the lines 10 and 11 and the short flap is folded down along the line 9 upon the inserted matches after which a bale C is cut to length, formed and applied upon the folded-down short 10

flap, fastened to place by partially turning in the bale ends under the body of the card, and the long flap is then folded down over the top of the short flap and overlying bale, around the match heads and down in under the packet to extend rearwardly past and under the partially crimped bale ends 21 to a little beyond the stick ends of the matches, and the bale is then crimped tightly at 21 upon the folded down long flap.

10 The bale C is provided with a sharp right bend at 22 (Figure 3E) that determines the thickness of the ignition chamber 23 and holds the turned-in edges 10 and 11 of the short flap so as to fairly tightly close the ignition chamber which 15 is the inside space between the spaced rows of holes, the ignition material being presented against the opposite sides of the match sticks at the forward end of this space.

When a match is withdrawn its head ignites 20 as it is being drawn through the ignition material upon opposite sides of the stick just back of the row of clean-cut holes 17.

The machine illustrated comprises stationary 25 frame structure D which gives housing and bearing support for the different machine elements that co-operate with one another and with the stationary structure to embody the invention.

The stationary frame includes legs D1, body D2 and a portion D3 at the left of Figure 1 for 30 supporting one end of an endless chain of match carrying blocks N.

The principal driving member comprises an 35 operating cam shaft E which is supported in spaced bearings ED (Figure 2) and may be driven at any suitable way as by a belt E1, pulley E2 that has suitable reduction gear connection E3 with the cam shaft E.

Each rotation of the cam shaft E starts a new 40 charge of matches through a stage of the match booking process, another scored and perforated card and another bale into the machine at different points and gives one complete cycle of operations for a number of different operating members that are respectively operating upon the successive match packets as the packets are passing or at rest at different parts of the machine. There are thus a number of different match 45 packets progressing through the machine simultaneously in different stages of completion and each rotation of the cam shaft effects a cycle of operations at each packet and progresses each packet to a new position for the next stage of operations.

The principal moving parts operatively connected to the cam shaft E include the members 50 F, G, H, J, K, L, M, N, P and Q.

The member F (Figures 15 and 18) is a plunger 55 adapted to horizontally reciprocate in a direction longitudinal of the length of the machine in a fixed guide FD.

The plunger F carries rigidly fastened to it a card feed blade F1 that delivers the bottom cards from the card supply hopper B1 and also with intermediate connections operates a member F2 to forwardly progress the partially completed packets through one step of their passage through the machine, as described later.

The plunger F (see Figures 18 and 17) has slot 60 and block connection F3 with a rocker member F4 which is pivoted at F5 and has roller and stud connection at F6 with a slot F7 in a barrel cam F8 upon the cam shaft E. It is preferably spring pulled rearwardly as indicated at F9, (Figure 2) to avoid any danger of lost motion.

75 The plunger G (Figures 17 and 18) recipro-

cates in a fixed guide GD and presents a head G1 that forms the card after it has been delivered by the plunger F1 and guides the matches when they are being threaded through the perforations in the card.

The plunger G is slotted at G2 to provide an operating engagement with the rounded end G3 of an arm G4 that is fastened to a shaft G5. This shaft is supported upon bearings G6 and carries an arm G7 which makes roller stud connection G8 with a cam slot G9 in the double acting face cam GE on the shaft E.

The plunger H (Figures 17 and 18) has a horizontal reciprocation forward and rearwardly in a stationary horizontal guide HD and presents rigidly fastened to it push rods H1 which charge matches into the blank beneath the match-guiding and card-forming head G1; it also operates through intermediate mechanism (best seen in Figures 1, 8 and 9A) described later push rods H2 which deliver matches from a match hopper A1 to match carrying blocks N for subsequent delivery to the push rods H1. The plunger H also carries short flap edge turn-in members H3 (Figure 15) and through intermediate mechanism H37 and H38 operates a short flap turn-down H4, Figure 18.

Each forward stroke of the plunger H thus pushes a charge of matches out of the match hopper A1, delivers a charge of matches into a 105 card underneath the match-guiding and card-forming head G1, turns in the edges of the turned up short flap of the card that is receiving its charge of matches from the push rods H1 and turns down the short flap of a packet that has 110 already been advanced to a later position.

The plunger H presents a stud and roller H5 into a slot H6 in a barrel cam H7 upon a shaft H8 which is supported in stationary bearings H9 and has miter gear connection HE with the cam 115 shaft E.

The vertically moving plunger J operates in a stationary vertical guide JD, presents a match stick guide J1 to the forwardly moving match sticks that are being pushed into the card by 120 the push rods H1 and also moves a registry pin J2 in position to properly register the match carrying block N that is presenting matches to the plungers.

The plunger J is provided with a downwardly 125 extending arm J3 which is perforated at J4 to surround the neck J5 of a double cam J6 upon the shaft H8. The arm J3 carries a pin J7 which carries rollers J8 that engage the lower surface of the cam J6. The plunger J is spring-pressed 130 upwardly at J9 and retracted positively by the cam J6. During each up-stroke it properly registers the match carrier block N and also presents match stick guides to receive the match sticks during the operation of the push rods H. It disappears downwardly before the match heads reach 135 the guiding grooves at J1.

The vertically reciprocating plunger K (Figures 27, 29, 28, 25 and 24) carries a bale shear K1, a bale forming punch K2, wedges K3 for registering the packet into position for applying the bale after the bale has been cut and formed and also carries a magnet K4 for holding the bale against the punch head K2 after it has been formed and after a cooperating die member L1 145 has moved out of the way.

The plunger K operates in a suitable vertical guide KD and is provided with a transverse slot K5 at which it makes a bearing engagement with the rounded end K6 of an arm K7.

The arm K7 is fastened angularly adjustably upon a shaft K8, angular adjustment being made at the set screw K9 in an extended portion K10 of the arm K7 after temporarily loosening a screw K11 fastening K7 to the shaft K8.

The shaft K8 is supported in bearings K12 (Figure 25) and carries a cam lever K13 which presents a roller K14 into a slot K15 in a double acting face cam KE on the shaft E.

10 The horizontal reciprocating plunger L presents a forming die L1 for co-operation with the forming punch K2, and also carries a projecting tongue L2 for gradual relief of the bale from the forming die L1 when the forming die moves back 15 to permit continued downward movement of the plunger K2.

15 The plunger L (Figures 15, 27 and 29) operates in a stationary horizontal guide LD and presents an upwardly directed bale-forming die member 20 L1, for co-operation with the punch K2, the plunger die L1 carrying an outwardly extending tongue L2 (Figure 39) for easier release of the formed bale when the lower die L1 moves back out of the way.

25 The plunger L has a block and slot connection at L3 with a rocker L4 which is pivoted at L5 and connects at L6 with one end of a link L7. The link L7 connects at its other end at L8 with the lever L9 that is loosely pivoted at L10 on a shaft L11 which carries rocker levers T of clincher 30 mechanism, described later.

30 The lever L9 makes a stud and roller connection L12 with the outside of a disc cam LE on the shaft E, the lever being spring-pulled at L13 to maintain contact with the cam.

35 The horizontal reciprocating plunger M (Figures 27 to 29B, 14 and 39A to 39F) operates a horizontal guide MD, presents at M1 a supporting seat for the packets during baling and carries a spring holder M2 that is operative to maintain 40 the turn-down flap turned down when the packet comes upon the seat M1 and that is subsequently operative to grip the packet when the plunger moves forward to transfer the packet to position for looping and clinching.

45 The plunger has a slot and block connection M3 with an arm M4 which is fastened to a shaft M5 having bearings M6.

The shaft M5 carries at its other end a gear 50 sector M7 having long teeth meshing at M8 with the teeth of a sector M9 which is pivoted at M10 and has an arm M11 carrying a roller M12 in the slot M13 of a barrel cam M14 upon a shaft M15. The shaft M15 is supported in bearings 55 M16 and makes miter gear connection MNE with the cam shaft E.

N (Figures 4A to 4C, 9A to 9C, 16A and 17) indicates match carrying blocks that successively receive charges of matches from the push rods H2 for subsequent successive presentation in front 60 of the push rods H1 for threading into successive cards B, the blocks together forming an endless chain.

65 Each carrier block N is mounted upon angle brackets N1 (Figure 16A) on a link of a sprocket chain N2 which passes over horizontally spaced idler guiding sprockets N3 and N4 around a lower idler sprocket N5 and a driving sprocket N6 (Figure 4B and Figure 5).

70 The sprocket N6 is mounted upon a shaft N7 that is rotatably supported in longitudinally adjustable bearings N8 that are integral with the bearings M16 of the shaft M15. The shaft N7 carries the slotted disc or driven member N9 of a Geneva, the co-operating driving member of

which N10 is mounted upon the shaft M15 which, as already explained, carries the cam M14 and makes miter gear connection MNE with the shaft E. The dwell positions of the blocks N are adapted to be adjusted for exact registry with the push rods H1 and H2 by means of simultaneous adjustments at N11 (Figure 4B) of the bearing support N12 of the sprocket N4 and at N13 (Figure 4A and Figure 6) of the bearings supporting the shaft N7.

80 A bale feed roll P (Figures 22A and 22B, 23 and 24) presents its knurled feeding face against a bale strip C upon the serrated face of a lower roll P1 with which the roller P co-operates to feed the bale strip C from a suitable spool C1 (Figures 1 and 2).

85 The roll P is rigidly mounted upon a shaft P2 which turns in bearings P3 near the outer end of a rocker member P4 pivoted on a pin P5 so as to present the roll P against the bale strip C upon the co-operating roll. A spring P6 having adjustable tension at P7 presses the roll P downwardly upon the bale strip C which is thus adjustably pressed between the rolls.

90 The spring P6 seats in a suitable recess of the 100 rocker at a point offset from the rocker pivot P5 and at its upper end engages the downwardly directed end of the stationary adjustable screw P7. The upper roll P is thus presented to its duty by the spring P6, supported in stationary housing 105 structure P6D.

95 Gears P8 and P9 fastened to or integral with the respective rolls mesh together so that both rolls must turn together without slip responsive to a feed applied to the roll P.

100 The shaft P2 of the roll P carries at the other end of its bearing P3 a ratchet wheel P10 (Figures 22A to 23) which is operated by a pawl lever P11 that is loosely pivoted on the hub of the ratchet wheel P10 and held in place by a collar 115 P12 pinned to the shaft P2. The pawl lever P11 carries the ratchet pawl P13, ratchet spring P14 and ratchet pin P15 and is operated by a link P16 to which it is pivotally connected at P17. The other end of the link P16 has a slot and pin connection P18 with the lever P19 which is pivotally supported at P20 (Figures 2 and 31) and presents a roller P21 in a slot P22 in a barrel cam PE of a cam shaft E.

110 The references Q indicate vertical plungers 125 (Figures 28A, 30, 31 and 32) spaced from one another longitudinally of the machine and operating in vertical guides QD. Each of the two plungers Q carries at its upper end a bale end forming member Q1 for partially turning in the bale ends 130 after the bale has been placed upon a partially folded match packet.

120 The plungers Q are spring-pressed downwardly at Q2 and carry nuts Q3 near their lower ends for limiting the upward strokes of the plungers.

135 The plungers present their lower ends on the upwardly directed ends of adjustable screws Q4 in the T-branched end of a rocker lever Q5 that is horizontally pivoted at Q6 and presents an upwardly directed engagement toe Q7 against the lower end of a plunger Q8. This plunger operates in bearings Q8D, is spring-pressed upwardly at Q9 and presents a roller Q10 at its upper end against the outside face of a disc cam QE which is clamped around the hub of the cam RE.

140 The reference R indicates a horizontal plunger (Figures 30, 31 and 32) that operates in a horizontal guide RD and itself angularly operates a looper member R1 which is mounted on a shaft 145

R2 in a bearing R3 and makes rack and pinion connection R4 with the plunger R.

The plunger R has a horizontally adjustable trunnion connection R5 with a rocker member R6 which has pivotal support at R7 and presents a roller R8 against a disc cam RE upon the drive shaft E, the lever being spring-pulled at R9 to maintain the roller against the cam.

The reference S (Figures 27, 33A, 33B, 39 and 25) indicates a plunger that operates in a horizontal guide SD and presents at its forward end a lower jaw member S1 for giving a vertically stationary support for a downwardly pressing upper jaw member S2 for gripping the match sticks 15 between the upper and lower jaw members during looping, and a projecting tongue S3 for downwardly bulging the looped over end of the long flap of the packet during looping and during final clinching, the tongue S3 also aiding in supporting the packet during looping and clinching.

The plunger S makes a slot and ball connection S4 with the upper end of a rocker member S5 which is loosely pivoted on a pin S6 and carries arms S7 and S8 which respectively present a roller S9 to engage the outside of a disc cam SE and provide anchor for a spring S10 which maintains the rocker so as to present the roller into the cam.

T indicates a rocker member (Figures 34, 35A, 35B and 35C) that presents duplicate wedge members T1 and duplicate rod members T2 for respectively positioning and operating duplicate jaw mechanisms for clinching the bale upon the packet.

The rocker T comprises horizontally spaced arms T3 and T4, the shaft L11 to which the arms T3 and T4 are keyed and which also loosely pivots the lever L9 operating the plunger L, and a downward extension T5 from the arm T3.

The shaft L11 has a stationary bearing support at RD. The arms T3 and T4 are alike except that one carries the downwardly extending arm T5 which presents a roller T6 against a disc cam TE on the cam shaft E. The rocker T is spring-pulled at T7 to maintain the roller T6 in contact with the cam TE.

The match charging mechanism includes the supply hopper A1 (Figures 1, 4A, 8, 9A, 9B, 9C, 10A, 10B and 10C), the reciprocating push rods H2, and mechanism for agitating and guiding the matches in the hopper as to insure the proper presentation of matches in front of the push rods during each forward stroke of the rods.

The hopper A1 comprises a stationary bottom portion A2, an intermediate portion A3 that has a slow short-stroke reciprocating movement in a direction transverse to the length of the matches and a stationary upper portion A4 that provides a major portion of the match content, flaring upwardly to increase its content.

The lower portion of the hopper comprises a series of parallel groove seats A5 that have their forward ends adjacent the conveyer and are in position to successively register with corresponding groove seats A6 of the blocks N at one position of dwell of the blocks N.

The groove seats A5 are too narrow to hold more than one match laterally but are deep enough to hold a number of matches, one atop of the other, desirably about five matches on top of one another in each groove.

The matches are placed in the hopper with the match heads all directed toward the front, that is toward the conveyer N2, and as the match heads are thicker than the match sticks the depth

of matches is greater at the front ends of the grooves than at the rear ends.

Each forward stroke of the push rods H2 takes place along the bottoms of the grooves and delivers the bottom matches in the grooves A5 of the hopper to the aligned grooves A6 of the match carrier N then at dwell in front of the match hopper.

Because of the greater depth at the head ends of the matches the upper walls of the grooves A5 slope rearwardly, the rearward slope being made such as to make the division line A7 between the lower and intermediate portions of the hopper parallel with the division lines between the matches adjacent the line of separation (Figure 9A).

The intermediate section A3 comprises a bottomless box having a bottom surface fitting the rearward downward slope at A7 of the bottom portion and an upper surface A8 having a greater slope, being substantially that of the matches adjacent the top of the intermediate portion.

The intermediate portion A3 is provided with a reciprocating movement and carries sloping wires A9, preferably about three wires when the charge of matches is to be ten for each packet. These wires A9 (Figures 10B and 9A) are parallel to the slope of the matches, are preferably all of the same elevation and vertically spaced a little above the bottom of the intermediate section. Their function is to assist in the settling of the matches into the groove seats A5 by preventing local bunching of the matches incident to the reciprocating movement of the section A3.

The transverse reciprocating movement may be applied to the intermediate section in any suitable way, one way being shown in Figure 8, where the hopper member A3 is adapted to reciprocate upon angle slide members A10. A link A11 pivotally connected at A12 to the hopper has its other end pivotally connected at A13 to a rocker member A14 having stationary pivot support at A15 and at its rearwardly extending end connecting to a link A16 which is connected to a suitable crank or eccentric A17 upon the shaft of a pinion A18 that in turn meshes with a larger pinion A2E upon the cam shaft E so that each rotation of the cam shaft effects a number of oscillations of the intermediate hopper portion to agitate the matches above the stationary body portion of the hopper in order to make more easy their entry into the upwardly directed grooves A5.

The upper portion A4 of the hopper is supported stationary on suitable uprights A4D.

The push rods H2 are operatively connected to the plunger H which carries an upwardly directed rack H11 (Figure 8) that meshes with a pinion H12 upon a shaft 13 having stationary bearing supports at H14 and H15 and carrying at its other end a pinion H16 which on its upper side meshes with a downwardly directed rack H17 upon a plunger rod H18 that is horizontally guided rearwardly and forwardly at H19 and adjustably rigidly connected at H20 to an arm H21 fastened to the plunger H22 carrying the push rods H2.

The push rods H2 are rigidly fastened to the plunger H22 which operates in stationary guides H2D and when the plunger is in its rearward position present their forward ends just back of the rearwardly directed ends of the bottom matches in the grooves A5.

The push rods H2 are preferably semicircular in section with the flat surface 24 horizontal and up and the curved surface 25 fitting the groove seat.

Each of the push rods H2 carries an upward projection 26 near its forward end which serves to stir up the matches immediately above the bottom matches during the forward stroke of the rods.

The push rods operate through suitable rearward and forward openings 27 and 28 at the ends of the groove seats A5, each forward stroke of the rods engaging the rear ends of the matches in the grooves A5 and pushing the row of matches out through the openings 28 on to the groove seats A6 of the conveyer block unit N that is registered in front of the push rods H2.

The plunger H and the push rod H1 and H2, as well as the short lap edge turn-ins H3 and the turn-down member H4 operate while the conveyer is in dwell.

As best illustrated in Figure 9A we may desirably increase the agitation of the matches in the hopper by vibrating the lower portion A2 of the hopper, or the matches in the hopper, either or both.

In Figure 9A we indicate diagrammatically means for introducing a pulsation of air pressure and vacuum in the bottoms of the groove seats A5 showing the bottom plate of A2 perforated at 29 and making conduit connection 30 with bellows 31 which is given reciprocation by a suitable cam 32 and operating connections not shown to the cam shaft E or to other suitable moving part of the machine.

It is desirable to make the match hopper adapted to give easy access to the bottom matches in the grooves A5 and we accomplish this by making the bottom plate A2 beneath the hopper removable, and/or as illustrated, by making the front of the hopper portion A3 as a hinged or sliding door 34, preferably with a glass front to give a sight feed of the matches.

The intermittently moving match carrying blocks N (Figures 1, 4A, 4B, 4C, 8, 9, 15, and 17) are guided by suitable horizontal guides ND to follow a straight and horizontal path from a point somewhat before the push rods H2 to a point somewhat beyond the push rods H1.

The blocks N are all alike each presenting the upwardly directed groove seats A6 in registry with the push rods H2 one dwell of the conveyer and in registry with the push rods H1 during a subsequent dwell of the conveyer.

The grooves A6 are a little longer than the match, adapting the blocks to use with matches of different lengths. The groove walls are chamfered away at 35 (Figure 9A) at their ends toward the match hopper, in order to avoid possible injury to the very thin walls of the grooves if any match sticks presented by the push rods H2 should register with the middle of any of the grooves. The other ends of the grooves have the bottoms of the grooves chamfered downwardly at 36 to provide more easy entry of the cupped ends 37 of the push rods H1 when the carrier N is presenting its load of matches for discharge into a packet.

There may be a considerable number of loaded carriers N intermediate the push rods H2 and H1 and one or more of those close to the push rods H1 are covered by a suitable cover plate 38 which closes the groove seats A6 across the top so that in effect the matches are enclosed in tube guides during discharge by the push rods H1.

Desirably a number of carrier blocks N intermediate to the two sets of push rods H2 and H1 are left uncovered to permit hand-placement of matches into any groove seats that have not been

properly charged by the push rod H2 or the replacement of any imperfect matches in the grooves by perfect matches.

Each carrier block presents a socket N14 to receive the registry pin J2 when the carrier is at dwell in position registering with the push rods H1.

The card hopper B1 (Figures 1, 11, 12, 13A, 16B and 18) comprises a box or vertical guideway for a pile of the cards B, and successively presents the successive bottom cards of the pile to the forward end of the horizontally reciprocating card feed blade F1 when this blade is in retracted position in a way that permits each bottom card to be pushed out from the bottom of the pile when the blade moves forward without disturbing any other card than the bottom card.

The hopper is supported by the bracket D4 that also carries the vertical guide GD of the plunger G, suitable screws B2 fastening the hopper to the bracket.

The hopper interior loosely fits the contour of the cards at the bottom but desirably spreads somewhat toward the top. As illustrated the hopper is made up of spaced channel members B3 and B4 held together at top and bottom by straps B5 and B6 respectively.

The lower strap B6 supports a heavy guide member F9 for the card feed blade F1, the member F9 casing the top of the blade and being vertically adjustably fastened at F10 to the strap B6.

The hopper is open between the channel members to give easy access to the cards and the channel members are preferably cut away at B7, B8 and B9 below the strap B6 for the same reason.

The cards B are placed in a pile in the hopper and a weight B9 is placed on top of the pile.

The cards, as already explained, are perforated, scored and provided with coats of ignition material, which results in the top of the pile being uneven and we find that in order to provide uniform pressure upon the bottom card the pressure applied at the top should not extend over the whole surface of the top card.

The weight B9 is provided with feet B10 and B11 which are fastened to the body of the weight, desirably adjustable longitudinally of the weight to present their bearing surfaces where experiment shows they most perfectly transmit a uniform pressure upon the bottom card.

The inside contour of the hopper fits the outside of the cards and the blade F1 which is slightly less thick than a single card pushes out the bottom card during each forward stroke, leaving all of the other cards in the hopper. In order to avoid more than one card moving forward during the stroke of the blade F1 a card guide member BD is placed along the discharge side of the hopper. The member BD presents an opening just right to pass one card but too low to pass more than one card at a time.

We register the cards that are delivered from the bottom of the hopper with respect to their edges that are toward the conveyer and provide a plate BD1 grooved at B12 to receive each card when it is pushed out of the hopper by the blade F1 and spring-press the other end of the cards to face the cards against the plate BD1.

The member B13 that resiliently presses the cards to face against the plate BD1 is best seen in Figure 13A and comprises a plate presenting a groove B14 over the edge of the card that is being delivered by the blade F1. The plate is loosely held down by the notched end of the plate

5 HD at the screw B15 at one end and by the head of the screw B16 at the other end, and presents to the card an easy chamfered entry into the groove, the card pressing back the plate against weak springs B17 upon rods B18 that extend rearwardly from the plate loosely through a flange D6 where they carry adjustable nuts B19 that limit the forward position of the plate.

10 The card is delivered by the blade F1 to a position to the right of the hopper for forming and charging with matches. The bottom of the seat is shown in the plan view (Figure 13A) and includes a flat plate 39 even with the bottom of the card hopper B1, the upper surface 15 of a resiliently upwardly pressed plate 40 (Figures 16A, 16C and 16D and Figures 19A to 19D) normally even with the plate 39 but adapted to be depressed by the forming die into a recess 41, and groove match stick guides 42 (Figure 20 16D) which are in a stationary plate held to place by a screw 43. The tops of the stationary grooves 42 are even with the top of the plate 49.

25 The card when first delivered by the blade F1 lies flat over the plates 39 and 40 and the tops of the groove guides 42 and faces at its front end in the groove B12 and at its back end in the groove B14 (Figures 13A and 19A).

30 The forming die G presents downwardly a card-forming and match-guiding head G1 having a contour directly above and slightly smaller than that of the recess 41 for the plate 40 and has downwardly directed groove seats G10 that align with the stationary grooves 42 when the head is depressed into the recess 41. These downwardly directed grooves G10 are cut transversely by an upward slot G11 to permit the plunger G to operate without affecting the position of a spring presser foot 44 which is supported at 45 from the card delivery side of the plunger housing GD (Figures 19A, 19B, 19C and 19D).

40 The punch head G1 is fastened to the lower end of the plunger G by suitable screws G12 that pass upwardly from the bottom of the recess G11.

45 The position of the card after it has been placed by the blade F1 is as illustrated in Figure 16A, where the card is faced against the fixed face plate B12 at the left of the figure and spring-pressed to its position by the plate B13 to the right. The forming die is vertically above the plate 40 which is spring-pressed upwardly at 46 from the recess 41 in the bed of the machine.

50 As the card feeding blade F1 moves back, the forming and guiding die G1 moves down and the conveyor comes to dwell presenting the seats A6 in the block N in registry with the push rods H1, the plunger J moves up registering the block N in exact position by reason of engagement of the pin J2 in the recess N14 upon the bottom of the block and presenting the match stick guide member J1 in front of the inwardly presented match sticks on the block N.

55 The forming die engages the card between the scored lines 5 and 7 (Figure 3A) which register with opposite edges of the recess 41.

60 The form moves on down into the recess turning the card at the scored lines 5 and 7 so that the long flap turns up at the back and the short flap turns up at the front, presenting the row of petticoated holes 16 in front of the downwardly directed grooves G10 in the bottom of the die and the corresponding clean-cut holes 17 at the rear end of these grooves.

65 The presser foot 44 has stationary support at 45 (Figure 14) on the housing of the plunger

GD and presents its spring foot a little above the card before the card has been depressed by the forming die and is in a vertical position to be resiliently deflected slightly upwardly by the match sticks after the match sticks have been loaded into the card and the card lifted by the plate 40 to its position for forward movement. It will be understood that the presser foot may have any suitable stationary support and comprises merely a spring positioned to downwardly engage the stick ends of the matches after the forming die has moved up in order to properly hold the packet for the engagement by the mechanism that transfers it to its next position.

70 While the die member G1 is in its depressed position, that indicated in Figures 16D, 17 and 19A, the push rods H1 move inward and present their cupped ends against the match heads and push the matches out of their seats A6 so that the sticks first enter the stick guide grooves J1 and then proceed inwardly through the petticoated holes 16 of Figure 3A along the grooves G10 in the bottom of the die G1 to thread through the holes 17 and into the stationary grooves 42 at the rear of the die (Figure 19A).

75 Before the match heads have reached the narrow guide grooves J1 but after the sticks have passed through the clean-cut holes 17 and while they are still progressing along the grooves 42, the match stick guide member J moves down out of the way in order to permit inward movement of the match heads which are too large to pass the relatively narrow grooves requisite for properly guiding the sticks at J1. The plunger rods H1 keep on advancing after the stick guide member has moved out of the way until the match heads are seated against the petticoated holes 16 which are at the bottom of the short flap.

80 During the inward movement of the plunger H to thread the matches through the card, the turn-in member H3 turns in the edges of the short turn-up flap along the scored lines 10 and 11, Figure 3A. This turn-in member is best seen in Figures 1, 15, 17 and 18.

85 This short flap edge turn-in mechanism is rigidly mounted upon the plunger H, spaced ears H24 and H25 projecting forwardly in positions to be presented along the lengths of the turn-in portions of the short flaps when the plunger H advances. The ears project from a body portion H26 Figure 19A to loosely include the card-forming and match-guiding plunger when the plunger H is in advanced position, the portion of the forward face of the plunger G1 intermediate the ears H24 and H25 being in effect a co-operating die member which co-operates with the plunger member H3 mounted upon the plunger H. The arms H24 and H25 at the end of the turn-in portion are chamfered outwardly at H29 from the edge of the casing member GD (Figure 18).

90 The stripper plate H30 is mounted intermediate the arms H24 and H25 upon suitable pins H31 and spring-pressed outwardly by springs H32 and adjustably limited from moving outward beyond the desired limit by heads H33 upon the pins H31 back across portion H34 that is rigid with respect to the plunger H and through which the pins loosely pass.

95 When the plunger H is in its advanced position the push rods H1 are presenting the match heads against the petticoated holes and the turn-in members H24 and H25 are overlapping the corners of the portion of the plunger G1 that is 100

intermediate the turn-ins breaking the turn-ins along the scored lines 10 and 11.

The plunger H moves out and the plunger G moves up which permits the plate 40 to spring-
5 press the threaded packet upwardly to a position above the walls of the stationary groove seats 42 in position to be engaged by the forwardly directed edge of the next card when this next card is pushed in by the card feed blade F1 on its next
10 stroke, which takes place during the next rotation of the cam shaft E. This next stroke of the blade F1 (Figure 37A) feeds another card into position beneath the card-forming and match-guiding member G1 and this card as it advances
15 pushes the packet that has just been threaded with matches into a position to be taken hold of by a mechanically moved ratchet member F2 operated by suitable connections from the plunger F, and during the succeeding stroke of the plunger
20 F in order to relieve the card pushed along by the blade F1 into position for forming and match loading from having to push more than one card ahead of it.

The ratchet member F2 (Figures 18, 20A, 20B, 25 21C and 26) operated by the movement of the plunger F has a range of longitudinal movement less than that needed for the member F and provision is therefore made for transmitting only a portion of the range of movement of the plunger
30 F to the member F2.

The ratchet member F2 is pivotally mounted at F9 upon a carrier member F10 which is longitudinally adjustably fastened at F11 to a square slide rod F12 and is adapted to slide along a fixed
35 rod F10D. The slide rod F12 is adapted to slide longitudinally in spaced stationary bearings F13 and F14 and is spring retracted to the left by a spring F15 (Figures 1 and 26).

The slide rod F12 makes an offset at F16 (Figure
40 18) from in front of the card hopper B1 to a position above the plunger F by which it is operated. The plunger F carries a bracket F17 that gives the rod F12 a bearing support at F18 from the plunger F.

45 During the forward stroke of the plunger F the bearing support F18 slides along the square rod F12 until it engages an adjustable collar F19 fastened upon the rod F12, after which the rod F12 is pushed along by the member F19 throughout
50 the rest of the stroke of the plunger F, and during the return stroke of the plunger F the spring F15 retracts the rod, maintaining the collar F19 against the rearwardly retracting member F18 until the rod F12 is stopped from further rear-
55 ward movement by an engagement between the upper end of the ratchet member F2 with the head of an adjustable fixed screw F20 and the subsequent engagement (Figure 20A) between a pin F21 carried upon the rocker ratchet member F2 and the end of a slot F22 in the member F10, which stops the rod F12 from moving further rearwardly.

60 The plunger F moves as much further rearwardly as brings it to the end of its return stroke, sliding with respect to the rod. The member F2 carries a pawl at its lower end adapted to push the match packet along during the forward stroke of the member F2 by its engagement back of one of the rearward matches of the packet and to
65 leave the packet in its advanced position on the return of the member F2. At the end of the return stroke of the member F2, the member is deflected against the retractive pull of the spring F23 about its pivot F9 by its engagement with the screw F20 in order to present the pawl into posi-

tion for the next forward stroke during which it will convey the next packet one step forward.

The packet that is being transferred a step forward by a forward stroke of the ratchet member F2 pushes ahead of it the packet that has been advanced by the preceding stroke of the member F2 into a position that is upon the transfer slide M1 but not yet in complete registry with the bale applying mechanism above the transfer slide, an additional movement of this forward packet being required to effect its registry at baling position. This additional movement is effected by wedge members K3 during the descent of the plunger K.

85 The packets are progressed from the match-applying position to the transfer slide along a suitable guideway (Figures 20A to 21C), each rotation of the cam shaft E advancing a packet one step and starting a new one on its way as well as completing an operating cycle of the different members at the different step positions.

90 The first step from the match threading position is that at which the packet is presented to the ratchet transfer member F2 and to which it is pushed by the new card entering the position for match threading. The second step, effected by direct engagement and stroke of the ratchet member F2 leaves the packet in position for the operation of the front flap turn down (Figures 21A and 21B). The third step, in which the packet after having had its front flap turned down is 105 pushed forward by the packet making the second step, places the packet on the transfer slide.

100 The fixed guide member 47 presents a forward edge 50 against the long flap 48 which is further guided by a plate D7 in Figures 21A and 21B which 110 shows the operation of the short flap turn-down plunger H4.

115 It will be seen that the rearwardly projecting match stems travel along a covered channel, that the long flaps project upwardly back of a fixed plate D6, the threaded matches passing under the plate.

120 It will be seen in Figures 21A to 21C that the guideway for the travelling packet includes the stationary bed plate 39, build-up plates 71 and 47 at the rear, build-up plates 72, 73 and 74 at the front and overhead plates D8 and D7 that are intermediate the up-turned portions 48 and 54 of the flap.

125 The guide plates 72, 73 and 74 at the front are fastened to the bed plate in any suitable way, not shown; the build-up plates 47 and 71 are shown fastened to the bed plates by suitable screws 75 and the stationary overhead plates D7 and D8 are fastened to a bracket 70 that is rigidly mounted 130 to the housing member GD.

The packet is left by the ratchet member F2 in position for the operation of the turn-down of the short flap which is effected by the plunger member H4 which moves in during the forward stroke of the plunger H so as to pass over the turn-up short flap and bend it down over a spring member 52 that is supported upon a stationary foot plate D8. The spring member 52 normally bows upwardly and that straightens out as 140 the blade of the turn-down plunger passes over it so as to present its forward edge 53 against the bend of the turn-in flap which takes place along the second line 8 (Figures 3A and 3C).

145 When the plunger H4 moves in it turns the short flap down so that its outer edge 54 passes beneath the bottom edge of a plate D9 (Figures 20A and 21B). This plate maintains the flap down after the blade member H4 retracts as seen in Figure 18.

The blade H4 is mounted upon a square bar H35 which is supported in fixed bearings H4D so that the bar is adapted to longitudinal movement. The bar is spring-pulled at H36 to retract it away from its operating position and the plunger H carries a projection H37 which is adapted to engage an adjustable collar H38 upon the rod H35 so that after the plunger H has reached a certain position in its forward movement the projection H37

engages the rod and pushes it forward to effect the turn-down, the spring H36 retracting the rod when the plunger H moves back until the retracting rod comes to rest by engagement between the blade H4 and one of the bearings H4D.

15 The forward stroke of the ratchet member F2 pushed a packet that was immediately ahead of that engaged by the ratchet member in position upon the transfer slide M1 but not quite in its position for receiving the bale C, the position being as indicated to the right in Figure 20A, which shows one of the wedge members K3 in dot-and-dash about to move down and push the right hand packet to its proper position for receiving its bale C.

25 Figure 21C shows a plan view of Figure 20A except that the packet at the right has been transferred to registry position on the transfer slide by the downward movement of the wedges K3.

The bale is fed from a suitable supply spool C1 to pass through the bale feed rolls P and P1 by ratchet feed of the roll P as already explained.

The bale is fed forwardly across the top of the lower forming die L1 (Figure 24) which is then in position for co-operation with the upper forming die K2 and comes to rest with the end of the bale against a stop C2 (Figures 24 and 26). The plunger K now descends and the shear K1 on the plunger K cuts the bale C to length and the descending punch K2 forms the bale upon the co-operating lower die L1 (Figure 28A).

The stop C2 for use in properly registering the position of the bale preparatory to the operation of the die member K2 is shown in Figure 26 as adapted to move to the left before the downward movement of the die member K2 in order to be out of the way of mechanism carried by the plunger K. In the illustration the stop C2 is a nose presented by a rocker member 80 which has pivot support at 81 upon the stationary plate D6 and is adapted to be swung upon its pivot from its operating position by the upward movement of a link 82 against the downward retraction of a spring 83. The forward position of the rocker is adjustably limited by a stop 84 and the link 82 has a loose operating connection at 85 with a rocker 86 operated by the plunger G.

When the plunger G moves up and down it rocks the member 86 which in view of the loose connection at 85 only affects the position of the link 82 during the low portion of the stroke of the plunger G. When the plunger G is at its lowest position it has raised the rod 82 and positioned the rocker 80 to that shown in dotted lines.

65 During this bale forming period the packet is moving upon the transfer slide M1 to the position shown in Figure 20A beneath the formed bale but a little to the left of perfect registry with respect to the bale.

70 After the bale has been formed, the horizontal plunger L retracts, the vertical plunger K moving up slightly to make the retraction more easy and presenting a narrow ledge K16 (Figure 29A) against the forward edge of the formed bale in

order to more easily strip the bale from the forwardly retracting forming die L1.

The plunger K is provided with an electro-magnet K4 which is in position to hold the bale in place when the forming die moves back from below the bale, and the forming die L1 is preferably provided with a tongue L2 (Figure 29A) which extends outwardly for a more gradual release from the bottom of the bale.

75 The tongue L2 prevents a sudden downward bowing of the bale C when released from the die L1, due to its own resilience and which has a tendency to break the bale away from the magnet and therefore lessens the requisite strength of the magnet.

80 After the forming die L has moved back out of the way the plunger K moves on downward and the wedge members K3 engage the edge of the packet (Figures 20A and 28A) and push the packet by wedge action into a position that is central with respect to the downwardly moving bale (Figures 21C and 28B).

85 The forming punch K2 carries hinged portions K17 at each side to turn down the ends of the bale, ends that are subsequently turned in by 100 clincher members Q1 that come up from below and during the continued downward movement of the plunger K for presentation of the bale C upon the packet the hinged portions K17 of the forming punch K2 swing away from the bale ends to 105 be out of the way of the operation of the bale clincher members Q1, wedge surfaces K18 on upwardly extending portions of the hinged members engaging stationary guide members K18D which turn the members about their pivots K19, 110 the lower die punches swinging outwardly as indicated in Figure 28B.

90 While the punch K2 and the co-operating magnet K4 which is set into the punch are presenting the bale upon the top of the packet, in dwell, 115 the plungers Q1 move up and partially turn in the bale ends C3 under the bottom of the packet in order to hold the bale in place upon the packet after the plunger K moves up out of the way.

95 During the transfer of the packet from its position for short flap turn down to position upon the transfer slide M1 the edge of the turned-down short flap is first engaged under the sloping ledge 55 presented by the plate D9 (Figures 125 20A, 21A and 21C) and subsequently passes beneath the raised spring member M2 upon the transfer slide M1 (Figures 20A, 21C, 27, 29A and 29B).

100 The lower edge 55 of the plate D9 that holds the short flap down after the retraction of the flap turn-down member H4 (Figure 21B) has a slight slope downwardly toward the transfer slide so as to move the turned-down short flap still further down as it approaches the transfer slide 135 M1 into position to pass under the spring member M2.

105 The spring member M2 is carried upon a raised portion of the transfer slide so that when the packet is pushed on to the transfer slide the 140 turned-down flap passes under the raised spring and is still held down before the descent of the bale. It is too far forward to be in the way of the descending bale-carrying member K2.

110 The spring member M2 is illustrated in Figures 145 29A and 29B. A body M18 of the member M2 is fastened to the top of a rocker member M19 by screws M20. The rocker member is pivoted at M21 to the transfer slide and spring-pressed up at M22 so that the spring tends to depress the 150

spring jaw M2 down upon the packet. The forwardly extending arm of the rocker member carries a roller M23 which is normally supported against the bottom of an adjustable wedge member M24 fastened to the frame structure D.

When the transfer slide moves to the right (Figure 29A) the roller M23 moves off the wedge member and permits the closure of the jaw M18 down on to the packet, under the action of the 10 spring M22.

This movement to the right takes place after the bale has been applied and the bale ends partially clinched under the packet to hold the bale in place upon the packet after the punch member K has moved up out of the way.

The magnet K4 is energized by any suitable electric connections K20, preferably the circuit opening to break the magnetism when the bale has been placed upon the packet and closing to 20 re-energize the magnet before the next retraction of the die member L1.

In the illustration the energizing circuit includes contacts 76 and 77 respectively on the stationary housing KD and the plunger K. These 25 contacts are located so as to be in engagement with one another for the positions of K at which it is desired to have the magnet effective and out of contact for the plunger positions at which it is desired to have the magnet ineffective.

30 After the bale has been applied to the packet and the forming plunger K has lifted, the transfer slide M moves rearwardly, to the right in Figures 27 and 29A, carrying the packet with it, pressing the rearwardly presented match sticks 35 so that their ends engage the V-entrance 78 (Figure 39E) between the match stick gripper members S1 and S2, forcing the spring-pressed member S2 up, and inserting the match sticks between the jaw members S1 and S2, the transfer slide M 40 stopping its rearward travel with the different parts in the positions shown in Figure 39F.

In practice this plate 59 may be dispensed with, the packet during its transfer from baling position passing between vertical guides 61 (Figures 45 39D and 39E) which true the packet so that the match heads align along a vertical surface 62 of the packet seat member M1.

When the transfer slide M approaches the position for looping, the long flap 48 passes under 50 a stationary low-bridge guiding plate 56 and transverse plate portion 57 of the looper which bend the flap down as indicated in Figures 33A and 39E.

Before the match stick ends reach the gripper members S1 and S2 they pass through openings 55 58 in a stop plate 59 (Figures 33A, 33C and 33D), the packet coming to rest against the prongs 60 of the plate.

As best seen in Figure 27, to accomplish this we 60 have fastened an arm M25 upon the shaft M5 of the rocker M4 that operates the transfer slide. The arm M25 presents a fork end M26 between loose sleeve members M27 and M28 upon a vertical fixed rod M29. Springs M30 and M31 above and below the respective sleeves are adjustably compressed by retaining collars M32 and M33 fastened to place on the rod M29.

After delivering the packet to match stick grippers S1 and S2, the transfer slide M retracts forwardly, leaving the packet held along the rearwardly projecting match sticks by the grippers S1 and S2, the hold of the spring gripper M18 on the transfer slide is relatively weak as compared to that of the jaw members S1 and S2.

The packet left in looping position, as in Figure

33A is also partially supported by the tongue S3 which extends forwardly under the packet between the partially turned bale ends.

We have found it desirable to spring press the transfer slide M toward a position that is intermediate its extreme positions so that as it approaches its end positions of travel it tends to spring retract to rest.

The match packet being now in position illustrated in Figure 33A, the looper member R1 rotates from the position shown full-line to that shown in dot-and-dash lines (Figure 33A) and on to the position shown in Figure 40B about the shaft. The pivotal axis of the looper coincides with the upper corner 63 of the packet when the packet is in looping position so that an angle portion R10 on the looper forms the match-head end of the packet at the scored lines 2 and 3 of the card (Figures 3A and 3C).

The looper arms R11 and R12 are relatively 95 spaced apart (Figures 34 and 39D) to straddle the tongue S3 when pressing the long flap to the position shown in Figure 40B, the tongue member S3 bulging the turned-up flap so that its opposite edges, at 64 (Figure 40C) pass between the 100 partially turned bale ends C3.

While the looper is in the position shown in Figures 40B and 40C, holding the long flap against the bottom of the packet and against the tongue S3, which is bulging the long flap downwardly between the arms of the looper, the rocker member T (Figures 35C, 35A, 35B and 40C) operates the final clinching of the bale ends.

The arms T3 and T4 move downward so that first the wedge members T1 move the clincher 110 slide members T8 inwardly so that clincher jaws include the partially bent bale ends (as in Figure 35A) and then the rod members T2 close the clincher jaws (as in Figure 35B) by downwardly deflecting the rockers T9.

The arms T3 and T4 then rise, permitting the springs T10 to retract the rockers T9, opening the jaws and the spring T11 retract the slides, moving the slides away from the sides of the packet.

The plunger S carrying the lower jaw S1 and 120 the tongue member S2 now retracts to the right, (Figure 40D) and permits the finished packet to fall to suitable chute or kick-off discharge not shown.

It will be evident that the groove seats A6 of the 125 match carrier block N, which present the matches in registry with the push rods H1, for threading into the card presented by the plunger G1, may be replaced by the groove seats A5 in the bottom 130 member A2 of the match hopper, in which event the match hopper will be placed so that the grooves will be placed so that its groove seats A6 present the bottom matches aligned with the push rods H1, and the match conveying mechanism 135 and push rods H2 will be omitted.

We have preferred to use the additional intermediate conveyer mechanism because its use permits hand replacement of imperfect matches after the operation of the plungers H2 but when 140 the grade of matches is such as to make unnecessary any such occasional hand replacement, we may omit the conveyer mechanism altogether and mount the match hopper directly in front of the charging rods H1.

The figures from 36A to 40D give a more or less diagrammatic illustration of the principal position of a single packet from the time that it receives the charge of matches until it is 150

discharged in finished state. The first packet is given designation *a*, and succeeding packets designations *b*, *c* and *d* so that in any figure the position of the different packets that are following the packet *a* can be seen.

In Figures 36A and 36B the bottom card in the hopper B1 is shown before it has been advanced to the position at the right for operation upon it by the card-forming and a match-guiding die 10 G1.

In the Figures 36C and 36D the bottom card has been advanced from the hopper B1 to the position beneath the die G1 which is not shown, the card lying flat and the presser foot 44 that 15 is fastened to the guard GD of the plunger G lying just above the card.

In the Figures 36E and 36F the card-forming and match-guiding die G1 has descended and is in dwell in its down position and the conveyor 20 block N has come to dwell, the match stick guide member J1 has risen registering the block N to exact position and the push rods H1 are about to advance to thread the matches A into the card B that has its short flap 51 turned up in front of 25 the plunger G and the long flap 48 turned up at the rear.

The short flap edge turn-in members H3 are also about to advance and the turn-in edges of the short flap are extending out straight beyond 30 the sides of the guard GD.

Figure 36F is a vertical section through Figure 36E upon the line 36F—36F.

In the Figures 36G and 36H the push rods H1 have advanced all the way in, inserting the 35 matches into the packet *a* and the short flap edge turn-in member H3 has advanced and is turning the edges of the short flap along the lines 9 and 10, Figures 3A and 3C upon the sides of the plunger G1.

40 Before the push rods H1 have moved the matches sufficiently far inward to bring the match heads into engagement with the match stick guide J1 (Figure 36H), the latter member has moved down to be out of the way of the match heads 45 which are too large to pass the groove guides in the member J1.

In Figures 36J and 36K the card-forming and match-guiding die G1 has moved up and the plate 40 in the recess 41 has followed the die upwardly 50 lifting the packet *a* until the bottom of the packet is even with the top of the plate 39 that initially seats the card before the forming operation, and the upper sides of the match sticks have engaged and slightly upwardly deflected the 55 presser foot 44.

The presser foot 44 extends across the match sticks and holds the packet firmly in place upon the surface of the plate 40.

The springs 46 beneath the plate 40 are relatively strong with respect to the downward spring of the presser foot so that the packet is in effect spring-pressed down by the presser foot at an elevation proper for being pushed forward by the next card when the next card comes from the 60 hopper B1.

The presser foot 44 has a forwardly extending portion 65 that overlaps the next position of the card so as to engage the rearward edge of the packet *a* after it has been advanced to the next 70 position registering with the forward edge of the packet *b* when the packet *b* is in the position shown for packet *a* in Figure 36K.

In Figure 37A the card-feeding blade F1 has 75 advanced and fed the card for the packet *b* into

position corresponding to that shown for packet *a* in Figure 36C.

The packet *a* has been advanced to the right by being pushed forward by the forward edge of the card for the packet *b* and its rearward edge is maintained in registry with the forward edge of the card for the packet *b* by the presser foot member 44.

In Figure 37B the card feeding blade F1 has retracted, the plunger G1 has descended; the packet *b* has been loaded with matches and is in the same position as that shown for packet *a* in Figure 36H.

The retractive movement of the plunger F has brought the ratchet member F2 into position to engage its pawl back of one of the rearward matches so that during the next advance of the plunger F the packet *a* will be carried forward to the right by the member F2 relieving the card for the packet *c* which is being then pushed out by the next stroke of the blade F1 from having to push ahead of it more than one packet, *b*.

In Figure 37C the plunger G1 has moved up and the packet *b* is left in the position shown for packet *a* in Figure 36K, and the blade F1 100 and ratchet member F2 are about to advance respectively to bring in a card for the packet *c* and to advance the packet *b*, the card for packet *c* pushing packet *b* one step forward.

In Figure 37D the advance of the members F1 105 and F2 has taken place. A card for the packet *c* has been placed in position shown in Figure 36C for the card of the packet *a*, the packet *b* occupying the position shown for the packet *a* in Figure 37A, and the packet *a* having been advanced to the right by the member F2 to a position that is a little to the left of the transfer slide M1 shown to the right.

During the movement to the right from the position shown in Figure 37C to that shown in 115 Figure 37D, the rearwardly extending match sticks pass under a horizontal plate D8 which extends from and is supported by a vertical plate D6 and is more clearly shown in Figures 21A and 21B.

A spring member 52 bowed upwardly upon the top of this plate is in position to be straightened out by the turn-down flap member H4 which operates upon the short flap when it occupies the 120 position of the packet *a* in Figure 37D.

In Figure 38A the plunger F has retracted carrying with it the card feed blade F1 and the ratchet packet-advancing member F2, the latter member being left in position for advancing packet *b* and the packet *a* being in position for the 125 operation of the short flap turn-down which is taking place in Figure 38B where the plunger F is still retracted, the packet *c* has been loaded with matches and the card-forming and match-guiding plunger G1 is still down, the position of packet *c* corresponding to that for packet *a* in Figure 36H, or for packet *b* in Figure 37B.

The operation of the short flap turn-down member H4 is shown perhaps more clearly on Figures 21A and 21B, the plunger member H4 moving in and sweeping the turned up short flap down upon the spring member 52 which flattens out with a resultant increase in width so as to present the forward edge of the spring 140 against the scored line 8, Figure 3A.

The push rods H1 and the short flap turn-down blade H4 are in their advanced positions at the same times and also in simultaneous retraction, as already explained.

- In Figure 38C the plunger H4 and the match push rods H1 are retracted and the vertically moving plunger G has moved up from the packet C which has been lifted by the plate 40 into position to be engaged by the next card during the next forward stroke of the card feed blade F1, the ratchet member F2 being retracted and in position to carry along with it the packet b during the next stroke of the plunger F. 80
- 10 In Figure 38D the plunger F has taken another forward stroke advancing the packets a, b and c each one step to the right and leaving a new card for the packet d in position shown in Figure 36C for packet a. 85
- 15 During the forward stroke to the right of the ratchet member F2 which is engaging the packet b the packet a has been pushed on to the transfer slide M1. 90
- 20 In the flap turn-down operation on the packet a the short flap 51 has been inserted beneath the sloping edge of the guide member D9 which holds the flap down after the retraction of the flap turn-down member H4. (Figures 21A and 21B.) 95
- 25 As the packet a is pushed on to the transfer slide M1 it is guided to pass under the raised spring member M2 (Figure 40A and 21C) mounted on a raised portion of the transfer slide M1 in front of the packet and at the end of the stroke of the ratchet member F2 has the position shown in Figure 38D, on the transfer slide with the short flap held down by the spring member M2 but at a position a little to the left out of registry with the bale which is being formed above the packet and is to be applied to the packet while the packet is upon the transfer slide but after the packet has been moved a little to the right by registry wedges K3 carried by the plunger K of the bale-forming mechanism. 100
- 30 Referring now to Figures 28A, 28B and 29A the bale C for packet a has been cut to length by the shear K1 mounted upon the plunger K and has been formed between the forming punch K2 and the die member L1 which is vertically beneath the punch K2 and vertically above the packet a. 105
- 35 The plunger L now moves rearwardly from beneath the bale C which is held to place by an electric magnet K4 initially assisted by a tongue L2 projecting from the die member L1 in order to prevent sudden bowing of the bale with a resultant strain upon the hold of the magnet K4 upon the bale C when the lower forming die L1 moves back. 110
- 40 The upper plunger K now moves further down pressing the wedges K3 to position to progress the packet from the position shown at the right in Figure 38D to that shown in Figure 21C and also shown in Figure 39A. 115
- 45 The downward movement of the plunger K presents the formed bale C upon the top of the turned down short flap and depresses the packet into a downwardly concaved surface of the transfer slide. 120
- 50 Initially the supporting surface offered by the transfer slide to the packet is horizontal, due to a flat spring member M34 that extends across the transfer slide under the match head ends of the packet as illustrated in Figures 29A and 21C and in the Figures 39A to F. 125
- The spring bridge M34 that supports the packet initially horizontally during its placement upon the transfer slide is illustrated in Figures 39A, 75 39B and 28A and comprises a flat spring suitably recessed into the slide at the sides so that along the sides of the slide, the slide and spring are of even height, and carrying a downwardly extending guide pin M35 that fits loosely into a suitable guide hole M36. 130
- The spring maintains itself straight under the mere pressure of the packet but yields downwardly when the plunger K is placing the bale upon the packet. 135
- In Figure 39A, the packet a has been registered to its proper position beneath the bale and the bale is being applied to the packet by the plunger K, the forming die plunger L1 having moved front out of the way. 140
- The downward movement of the plunger K carrying the bale has depressed the packet from a horizontal position in which it was initially held by the spring member M34 to accord with the upwardly directed concave surface presented by the top of the transfer slide. 145
- The plungers Q1 for turning the bale ends in under the packet are now moving up, and in Figures 39B and 28B the plungers Q1 have moved up and turned in the bail ends to hold the bail in position after the upper die member K moves up out of the way. 150
- This plunger is still down in Figure 39B, but is about to move up. 155
- In Figure 39C the plunger K has moved up out of the way of the packet, the plungers Q1 after having turned in the bail ends sufficiently to hold the bale in place have moved down, and the transfer slide M1 is ready to move rearward to bring the packet to its position for looping and final clinching. 160
- It will be seen that the spring support M34 beneath the forward end of the packet has straightened up after the plunger K has moved up, so that in Figure 39C the packet is again substantially horizontal upon the transfer slide. 165
- The spring jaw member M2 at the forward end of the transfer slide is still in raised position, and after the bale has been applied to the packet, the packet may make a very loose connection with the spring jaw M2 which shuts down upon the packet when the transfer slide moves toward the looping and clinching position. 170
- Figure 39D corresponds to a section upon the line 39D—39D of Figure 39C, showing the parts in the same position that they have in the latter figure, and in the same way Figure 39C corresponds to a section taken upon the line 39C—39C of Figure 39D. 175
- Figure 39E is a vertical section on the Figure 39D, with the parts in the same position that they occupy in Figure 39C, with the transfer slide M1 about to move to the right to bring the packet a to position for looping and final clinching. 180
- In Figure 39E the transfer slide has moved to the right and presented the ends of the match sticks through openings 58 in a register plate 59 (Figures 33C and 33D) into the chamfered approach 55 to the match stick grippers S1 and S2, 185 forcing the rearwardly projecting match sticks between the grippers by lifting the member S2 so that at the end of the rearward stroke of the transfer slide M1 the match stick ends are firmly held between the jaw members S1 and S2. 190
- The tongue member S3 projects from the lower jaw member S1 out under the packet. 195
- During the movement of the packet past the looper, the long flap 48 has been engaged by the transverse members 56 and 57 (Figure 33A) which 150

has bent the long flap forward over the packet as seen in Figure 39F, the looper R1 still being raised.

During the travel of the transfer slide to the right from position shown in Figure 39E to that shown in Figure 39F, the packet has been aligned so that the match heads face against the rearwardly directed abutment shoulder 62 at the front end of the packet, by reason of the packet having to push its way between vertical guide member 61, the packet having to straighten up in order to pass between the guide members, and being pushed a little rearwardly, so as to bring the match heads aligned against the shoulder 62.

In Figure 40A the transfer slide has moved forward again to its receiving position where it receives the packet *b* while the packet *a* has been left held by the rearward projecting sticks in the jaws S1 and S2 and by the projecting tongue member S3, which extends under the packet, and the packet is in position for the operations of looping the long flap, of finally clinching the bale ends and of discharging the packet *a* as a finished match book, operations already described and illustrated in Figures 40B, 40C and 40D.

In view of our invention and disclosure variations and modifications to meet individual whim or particular need will doubtless become evident to others skilled in the art, to obtain all or part of the benefits of our invention without copying the structure shown, and we, therefore, claim all such in so far as they fall within the reasonable spirit and scope of our invention.

Having thus described our invention, what we claim as new and desire to secure by Letters Patent is:

1. The method of feeding matches from the hopper to a partly formed apertured package blank, which consists in feeding the matches longitudinally head forward in a group for one package to a position for transfer, in transferring them laterally to a position aligned with the apertures in the package while giving opportunity for inspection of each group and in feeding them stick end foremost longitudinally and simultaneously into the apertures of the blank.

2. The method of guiding matches fed from a delivery mechanism to a partly formed apertured match book blank, which consists in feeding the matches end for end from the delivery point with the stick end first, in supplying guides for the stick ends to cause them to enter the package blank and in withdrawing the guides as the heads approach the guiding position.

3. The method of guiding, forming and filling an apertured package blank with matches, which consists in cupping the blank by pressure exerted at intervals across the surface of the blank between the match positions and in forcing the matches through the apertures in the blank at points between the points of pressure upon the blank.

4. The method of guiding, forming and filling a package blank with matches, which consists in cupping the blank by pressure at intervals across the surface of the blank, in forcing the matches across through the blank at points between the points of pressure upon the blank and finally crimping the edges of one of the cupped ends of the blanks concurrently with termination of the filling movement.

5. The method of transferring matches from a conveyer to an apertured match blank, in which they are to be inserted in formation of a match package, which consists in holding a flat blank

at a point between the perforations, in shifting the blank transversely to its plane, while turning the ends of the blank up to bring the perforations in line, in supplying the matches in line with the perforations, and in threading the match sticks through the perforations by movement of the match sticks lengthwise, stick end first.

6. Steps in the method of filling match blanks with matches, and folding the blanks to form a package, which consist in feeding the matches and flat apertured blanks to positions opposite each other for threading matches, in folding the blank to bring the apertures in the blank in line, in threading the matches through the apertures, in shifting the blank containing the matches to a third position by the lateral feed engagement of a second blank, and separately engaging the blank to a fourth position free from engagement with following blanks.

7. Steps of the method of making a match package from matches and a preliminarily apertured flat blank which consists in cupping the blank to bring the apertures in line, feeding the matches lengthwise, stick first, through the apertures, moving the partly filled blank laterally to 100 the match length to a position of rest, at the said rest position turning down a flap of the blank over the matches, and in again laterally continuing to hold the flap down.

8. Steps in the art of making match packages from apertured flat blanks and matches, which consists in cupping the blank to provide opposite apertured blank flaps with an intermediate horizontal blank portion, feeding the matches 110 through the apertures to provide the matches of the package, laterally shifting the blank to a position of rest, turning down one of the flaps, temporarily holding the flap down, in progressing the package laterally to the matches while maintaining the hold, and permanently binding the flap down by pinching the edges of the flap.

9. The steps in the manufacture of match packages to turn down a flap at the end of a plurality of matches threaded longitudinally into 120 a match blank, which consists in turning the flap down and in concurrently outwardly pressing the flap along the line of bending.

10. The steps in the manufacture of match packages to turn down a flap at the end of a 125 plurality of matches threaded longitudinally into a match blank, which consists in concurrently supporting the flap adjacent the matches from inward movement and in turning the flap down along the line of support.

11. The steps in the art of manufacture of match packages to make a bend between a flap and a blank containing a plurality of matches threaded longitudinally into a match blank, which consists in concurrently downwardly bending the 135 flap and outwardly pressing the flap along the line of bend, in relieving the pressure along the line of bend and subsequently shifting the package parallel to the bend.

12. Steps in the method of folding a blank 140 having parallel rows of apertures in the formation of a match package, and in retaining the blank in folded position, which consist in cupping the blank, inserting the matches through the 145 apertures in the blank, folding one of the flaps, formed by the cupping, longitudinally over the matches, transversely moving the package to a new position while maintaining the flap in folded position, temporarily holding the flap down by 150

- edge connection with the bottom of the cupped portion, turning down the other flap about the package and securing it at its edges beneath the cupped portion.
- 5 13. The method of securing the flaps of a match package in closed position by a bale, which consists in folding in one of the flaps of the package, in applying the bale to tentatively hold the flap in position, in folding the opposite end of the flap about the package, and beneath the ends of the bale and closing the ends of the bale to secure the package. 80
- 10 14. The method of folding and holding by a bale the flaps of a match blank in formation of a match package, which consists in folding down one of the flaps of the blank, in tentatively holding it in position, in transferring the package laterally to an additional position while holding the flap down, in applying the bale to the flap and body of the package, to afford temporary holding of the first flap, leaving the ends of the bale partly open, in folding the second flap of the package about the end of the package bringing the edges of the flaps into engagement with the ends of the bale so that the open ends pass through the flap near the edges thereof, and in finally closing the ends of the bale to permanently hold the two flaps closed. 85
- 15 15. The method of forming a match package, which consists in cupping a previously apertured blank to bring the apertures in line and form short and long flaps in filling the apertures with matches, in laterally moving the blank with the matches in place, in folding down and temporarily holding the short flap of the blank, in laterally moving the package while holding down this flap of the blank, in folding the second flap of the blank, and in holding the package by the projecting stick ends of the package while the second flap is being folded. 90
- 20 16. In the method of forming a package from a blank and matches held together by a bale, the steps which comprise folding down a flap of the blank over the matches, cutting and forming a bale above the blank, holding the bale electro-magnetically, pressing the bale to place about the blank, and closing the ends of the bale partially about the blank to hold the parts temporarily in position. 95
- 25 17. The method of forming a package from a blank and matches held together by a bale, the steps which comprise folding down a flap of the blank over the matches, cutting and forming a bale above the blank, holding the bale electro-magnetically, pressing the bale to place about the blank, closing the ends of the bale partially about the blank to hold the parts temporarily in position, subsequently folding the other end of the blank about the matches and turning its edges in beneath the partly open bale ends, and closing the bale ends against the second end of the blank. 100
- 30 18. The method of forming a package from a blank and matches held together by a bale, the steps which comprise folding down a flap of the blank over the matches, cutting and forming the bale above the blank, holding the bale electro-magnetically and pressing it to place about the blank, closing the ends of the bale partially about the edges of the blank to hold the parts temporarily in position, subsequently turning the other flap of the blank about the match heads to a position with its edges in line with the position beneath the ends of the bale, but with the intermediate portion outwardly displaced to pass the edges of the end of the blank beneath the bale ends, flattening out the end of the flap to extend beneath the ends of the bale, and crimping the ends of the bale shut to hold the edges of the blank firmly beneath the bale ends. 105
- 35 19. The method of forming a sharp edge in bending a flap of pasteboard which consists in concurrently forcing the flap progressively downward using the downward movement of the flap to sharpen the bend. 110
- 40 20. The method of forming a sharp bend in a match package in which a flap is being bent about the head ends of the package, which consists in forming the intended contour of the flap end for the package in the bending member and in pressing the package lengthwise of the matches and against retardation by means of the bending member pushing against the packet at the folding flap adjacent the head ends of the matches. 115
- 45 21. In the manufacture of match packages from matches, covering material and a retaining bale, the method of forming the package which consists in bending the covering material to cup it, in inserting the matches endwise through the sides of the cup, in bending down one of the flaps of the cup over the matches, in shaping the intended bale above the package, in forcing the bale downwardly upon the package, in turning the ends of the bale temporarily to hold the bale in position while holding the flap down, in turning the second flap down over the length of the package, in bending the second flap about the head end of the package and to a position beneath the bale end and in closing the ends of the bale to hold the package in final position. 120
- 50 22. In a match machine, a holder adapted to present a plurality of spaced matches corresponding to the matches of one match book, means for feeding the matches longitudinally and a conveyer intermittently movable transversely to the direction of the match feed, said conveyer being adjacent to the matches fed and having ribbed sections, each section to receive between the successive ribs thereof the matches corresponding to one book, and during rest in receiving position longitudinally registering the receiving spaces intermediate the ribs with the matches of the holder. 125
- 55 23. In a match machine, a holder adapted to present a plurality of spaced matches corresponding to the matches of one match book, means for feeding longitudinally the spaced matches out of the holder, a conveyer movable transversely to the direction of the match feed, adjacent to the head ends of the matches fed and having ribbed sections, each section to receive the matches corresponding to one book, means for moving the conveyer and discharging means for the conveyer pushing the matches from the conveyer longitudinally in a direction opposite to that of charging. 130
- 60 24. A match conveyer made up of ribbed sections having spaces for matches corresponding in each section to that of one match book, a step-by-step means for moving the conveyer a distance corresponding to the spacing of the sections, charging means for delivering the matches longitudinally section-by-section, packaging-presenting-mechanism for presenting and holding an apertured package to receive the matches in position adjacent to the conveyer, charging mechanism engaging the matches upon a section and discharging them from the conveyer in a direction opposite to the direction of charge into open- 135
- 65 70 75 140

- ings in the package and connections between the charging and discharging mechanism whereby they operate alternately.
25. In a match-packaging-machine, a lateral feed for a card blank, a registering guide for the one end of the blank and a spring-pressed plunger for the other end of the blank holding the blank against the registering guide during its lateral movement.
- 10 26. In a match-packaging-machine, a hopper for blanks having a lateral delivery opening, a fixed guide for the front of the blank as it emerged from the hopper and a resiliently pressed guide having a grooved face engaging the rear of the blank to hold the blank against the fixed guide.
- 15 27. In a match-packaging-machine, a match carrier having grooves to hold the matches and adapted to deliver the matches lengthwise to a match package, a blank-cupping vertically movable upper die and a combined cooperating lower cupping die and guide for the individual matches between the carrier and the match package aligning with the grooves and receiving and guiding the individual match sticks as they emerge from the carrier.
- 20 28. In a match-packaging-machine, a match carrier having grooves to hold the matches and adapted to deliver the matches lengthwise to a match package, a guide having grooves aligned with the grooves of the carrier and located between the carrier and the match package for receiving and guiding the match sticks as they emerge from the carrier, means for inserting and withdrawing the guide from guiding position to permit feed of the match sticks along the guiding grooves and the match heads over the guiding grooves of the withdrawn guide.
- 25 29. In a match-packaging-machine, a match carrier having grooves to hold the matches and adapted to deliver the matches lengthwise to a match package, a guide having upwardly directed grooves aligned with the grooves of the carrier and located between the carrier and the match package for receiving and guiding the individual match sticks as they emerge from the carrier and positive actuation for the guide to move it downwardly out of the way when the heads of the matches approach it.
- 30 30. In a match-packaging-machine, a match carrier having grooves to hold the matches and adapted to deliver the matches lengthwise to a match package, a guide having grooves aligned with the grooves of the carrier and located between the carrier and the match package for receiving and guiding the individual match sticks as they emerge from the carrier, means for shifting the guide into position to perform its function and a centering and locking mechanism for the carrier movable with the guide.
- 35 31. In a match-packaging-machine, operating upon blanks having spaced openings into which the matches are threaded longitudinally, an upper vertically movable die having downwardly directed grooves for receiving the matches, and a lower die cooperating with the upper die for cupping a blank and including a downwardly movable plate under the upper die and stationary members out from under the upper die upon opposite sides of the plate, one of the stationary members comprising a guide having upwardly directed grooves aligned with the grooves of the upper die when the upper die is in cupping position.
- 40 32. In a match-packaging-machine operating upon blanks having spaced openings into which the matches are threaded longitudinally, an upper die having downwardly directed grooves for receiving the matches, a lower die including a downwardly yieldable plate under the upper die and having an upwardly directed plain surface, and stationary members out from under the upper die respectively adjacent opposite sides of the plate, one of the stationary members comprising a guide having upwardly directed grooves aligned with the grooves of the upper die when the upper die is in cupping position and a folder blade movable transversely to the upper die and operating with it to bend the edges of one side of the cup.
- 45 33. In a match-packaging-machine, an upper die having match guides on the lower end of it, a vertically movable plate against which the upper die presses the match cover blanks with downward deflection of the plate, side guiding members adapted to turn up the flaps of the package and match inserting mechanism pushing the matches into apertures in the blank while the die holds the blank against the plate.
- 50 34. In a match-packaging-machine, a cupping device for cupping a blank, a feeding device for feeding matches into the cupped blank, a flap turning device for bending one of the flaps down against the matches and a retaining ledge beneath which the outer edge of the flap is snapped to temporarily hold the flap in that position.
- 55 35. In a match-packaging-machine adapted to operate upon a cupped blank having matches in position and one flap turned further than the other flap, a flap-turning device, a guide over which the flap is bent to give the flap a sharp bend and temporary retaining means for holding the flap down while the partly finished blank is shifted to another position.
- 60 36. In a match-packaging-machine, blank cupping mechanism, feeding mechanism for inserting matches within the cup, means for turning down one of the flaps and holding it in turned position, shifting means for longitudinally moving the partly finished blank, bale-applying mechanism for further holding down the flap, longitudinally shifting mechanism for moving the partly finished package to a new position and a gripping clamp adapted to hold the package in the new position while the longitudinally feeding mechanism returns to its position.
- 65 37. Steps in the method of making a match package from matches and a previously apertured flat blank, which consists in forming the blank to cup form, to bring the apertures in line, feeding the matches lengthwise, stick first, through the apertures, moving the partly filled blank laterally to the match length, in turning down a flap of the blank over the matches by movement lengthwise of the match blank, and temporarily holding the flap depressed while the blank is advanced to the next position.
- 70 38. In a match-packaging-machine, a packet seat member for presenting a partially folded match packet to a downwardly covered bale-applying member, the seat presenting a downwardly concave face beneath the packet, and a horizontal bridge across the concavity adapted to yield downwardly while placing the bale upon the packet.
- 75 39. In a match-packaging-machine, a concave seat for presenting a partially folded packet to a bale-applying member adapted to move down and to apply a bale to the packet, wedge members for centrally registering the packet with respect to the bale-applying mechanism, and means for placing the packet partially upon the

- seat presenting a horizontal support for the packet during its placement upon the seat and during its registering movement by the wedges and adapted to yield downwardly in order to permit the packet to be pressed into the concavity of the seat. 80
40. In a match-packaging-machine, means for forming a partial package having matches in place, one flap of the package down over the matches and another flap extending upwardly, feeding mechanism moving the package laterally to approximately a baling position, edge-engaging-mechanism coming in contact with the edges of the package to center the package and bale-applying mechanism forming a bale and partially closing the bale about the package in the centered position. 85
41. In a match-packaging-machine, means for feeding a partly finished package laterally and centering mechanism for placing the package for a baling operation, comprising vertically movable wedges of convex cross-section chamfered at the edges to engage the package in the middle inner portion of the wedges. 90
42. In a match-packaging-machine, a transfer slide having a guard adapted in certain positions of the slide to engage the top of the partly finished match package, means for feeding the match package laterally of the package to the slide so that a flap upon the package goes under the guard, means for moving the slide with the package longitudinally of the package while the flap is held down by the guard and means for binding the guard upon the flap of the package as the slide moves longitudinally of the package. 95
43. In a match-packaging-machine a lateral feed for a partially formed match package, a transfer slide into which the package is fed, means for moving the transfer slide longitudinally of the match sticks of the package, a guard on the transfer slide under which a flap of the package is fed and means effective with movement of the transfer slide causing the guard to grip the package. 100
44. In a match-packaging-machine, a transfer slide adapted to move a partly completed package stick end first longitudinally of the sticks, an abutment upon the slide against which the match heads are adapted to be registered and a clutch engaging the stick ends of the matches so that movement of the package presses the heads toward the abutting face. 105
45. In a match-packaging-machine a spring jaw clutch adapted to receive the stick-ends of matches and to be forced open by them and a transfer device for moving a partially completed package stick end first into the clutch. 110
46. In a match-packaging-machine, a transfer slide adapted to move a match package having projecting match sticks longitudinally of the sticks, a holder on the slide engaging the package and a clutch into which the stick ends are fed having a stronger hold upon the match package than the holder whereby as the transfer slide is retracted the clutch holds the package for a further operation. 115
47. In a bale-applying mechanism for a match package a vertically movable upper die, a horizontally movable lower die, and a vertically movable closing die, means for moving the upper and lower dies to engage in the formation of a bale, means for withdrawing the lower die, means for lowering the upper die into engagement with the package and means for lifting the closing die to turn the ends of the bale. 120
48. In a machine for packaging matches using a blank and matches therein, operating upon a match package having matches in place and a long flap free, means for moving the package so as to throw the flap over one end of the package, a gripper engaged by the match sticks during this movement to hold the package and revoluble folding mechanism engaging the remainder of the flap and turning it about the match heads. 125
49. In a match-packaging-machine adapted to operate upon a match blank having matches in the blank, a long flap extending upwardly and a short flap bent over the matches, a bale forming mechanism, means for placing the bale about a partially completed package leaving one flap free, means for partly closing the bottom of the bale about the package, flap turning mechanism for turning the remaining flap about the package, and for inserting its edges beneath the partly open ends of the bale, and means for closing the bale ends to hold the package together. 130
50. In a match-packaging-machine, means for forming a package having matches in it, a free long flap and a short flap closed over the matches, a bale holding the parts in position, a revoluble flap-turning mechanism swinging the end of the flap about the structure of the package and beneath the ends of the bale and closing means for the ends of the bale to engage the edges of the flap turned. 135
51. In a match-packaging-machine, a clutch adapted to hold a partly finished match package having one flap extended and a looper for turning that flap about the package and giving a square end to the turn, comprising an arm pivoted approximately in line with the beginning of the turn and having a flat transverse seat in final position engaging the end of the flap transversely to the lengths of the matches and pressed against the heads of the matches. 140
52. In a match-packaging-machine, a holder for a nearly completed match package having an extending flap, a looper adapted to turn the flap around the end of the package and a thrust receiving member adapted to be moved into and out of position between the package and the flap after it has been looped to take the thrust of the looping movement. 145
53. In a match package flap turn-in mechanism, a support adapted to lie directly over the match package at a distance lengthwise of the match from the match heads, a spring upon the top of the support extending longitudinally of the matches and free to move lengthwise and a flap-folding member turning the flap about the end of the spring and in its movement flattening out the spring to extend the end of the spring so as to give a sharp corner to the fold. 150
54. In a match package flap turn-in mechanism a support adapted to lie directly over a scored match package at a distance lengthwise of the match from the match heads, a spring upon the top of the support extending longitudinally of the matches and free to move lengthwise and a flap-folding member turning the flap about the end of the spring and in its movement flattening out the spring to extend the end of the spring so as to give a sharp corner to the fold and a ledge under which the flap is adapted to be presented in folding and which temporarily holds the flap in position. 155
55. In a match-packaging-machine, means for 160

holding a nearly completed package in position for looping the flap, a looper having spaced arms adapted to turn the flap to final position and a tongue adapted to lie between the flap and the rest of the package in the final position of the flap and means for moving the tongue into and

out of position, whereby the flap is concave to present its edges under the ends of the bale.
